UNITED STATES PATENT OFFICE.

JAKOB SCHAFER, OF NEW YORK, N. Y.

MEDICINE-CHEST.

SPECIFICATION forming part of Letters Patent No. 678,284, dated July 9, 1901.

Application filed January 17, 1901. Serial No. 43,657. (No model.)

To all whom it may concern:

Be it known that I, JAKOB SCHAFER, a subject of the Emperor of Austria-Hungary, residing at Manhattan borough, New York city, in the county and State of New York, have invented new and useful Improvements in Medicine-Chests, of which the following is a specification.

This invention relates to a medicine-chest specially adapted for home or household use and which enables the requisites for a sick-room to be readily stored or kept at hand and by which those requisites specially in use at any given time can be kept within easy reach either of a patient or an attendant, while directions or required memoranda can be kept exposed to view.

This invention is set forth in the following specification and claims and illustrated in the annexed drawings, in which—

Figure 1 is a view of the chest opened, showing the inside of the top cover or lid. Fig. 2 is a sectional view of the chest, the covers or lids supporting each other at a suitable angle or exposure.

The chest A is divided into three compartments, indicated at 1, 2, and 3, the latter containing, for example, bottles 4, and the other compartments can hold powder or like boxes or also cotton, plaster, and other sundries, or ice, if required, for keeping a remedy cool. A suitable opening or drainage for emptying or to allow the melted ice to run off can be provided.

The chest is provided with two lids or covers, the inner lid 5 and the outer lid 6, hinged, respectively, at the front and rear of the chest or box A. The outer lid has the loop or hasp 7, which when the chest is closed engages with a similar fastening or staple 7' at the front of the chest, so that the latter can be locked, as well known. When, however, both lids are opened, as to the position shown in Fig. 2, the loop 7 of outer lid 6 engages the hook or attachment 5' on the inner lid, so that the latter is held at a suitable angle or exposure, and its articles and writing can thus be readily grasped and seen. On such inner lid can be placed, for example, a watch at the hook 8,

and in connection therewith the dial 9 is provided, its hands 9' being set by the attendant or user, the interval, as one and one-half hours, being determined by the instruction on the slate or writing-face 10 in connection with the time indicated by the watch or by a suitable striking or bell mechanism indicating the time for taking medicine. Another tablet or slate, as 11, states the nature of the treatment—as, for instance, medicine which is to be administered in amounts indicated by slate 12, for example one teaspoonful.

The several instructions given can of course be of a different nature—as, for instance, slate 11 may direct that pills be given, poultices applied, injections performed, &c. Likewise on slates 10 and 12 can be written diverse remarks or instructions, for which purpose the pencil 13 is provided. The lid also contains holders for bottles 14 and for spoons 15. The outer lid is also provided at its inside with 70 holders, as 16, for syringes and with cross-strips or holders 17, the latter forming a compartment for containing various kinds of surgical instruments, as breast-pumps, scissors, and the like. The inner cover 5 when closed 75 is supported by the ledges 18, secured at the two rear corners of the chest. The chest A serves as a base or support for the lids 5 and 6, so that these lids can be conveniently set on a table or transported to any point required. 80

What I claim as new, and desire to secure by Letters Patent, is—

1. In a medicine-chest, a case having a plurality of compartments, an inner lid hinged at one edge inside the case at one side thereof, 85 an outer lid hinged to said case at the opposite side thereof and having a loop or staple, a staple on the case to be engaged by said loop or staple when the outer lid is down, and a hook on the free edge of the inner lid to be 90 engaged by said staple when the outer lid is raised to thereby maintain both lids at an angle to each other.

2. In a medicine-chest, a case having a plurality of compartments, an inner lid hinged 95 at one edge inside the case at one side thereof, an outer lid hinged to said case at the opposite side thereof, and having a loop or staple,

a staple on the case to be engaged by said loop or staple when the outer lid is down, a hook on the free edge of the inner lid to be engaged by said staple when the outer lid is raised to 5 thereby maintain both lids at an angle to each other, and erasive tablets and time-indicating means on one of the lids.

In testimony whereof I have hereunto set my hand in the presence of two subscribing witnesses.

JAKOB SCHAFFER.
